UNITED STATES PATENT OFFICE.

FRANCIS M. HUNT, OF OSSEO, MICHIGAN.

IMPROVEMENT IN EGG-CARRIERS.

Specification forming part of Letters Patent No. 149,479, dated April 7, 1874; application filed August 27, 1873.

To all whom it may concern:

Be it known that I, FRANCIS M. HUNT, of Osseo, in the county of Hillsdale and in the State of Michigan, have invented certain new and useful Improvements in Egg Carrier and Inspector Combined; and do hereby declare that the following is a full, clear, and exact description thereof, reference being had to the accompanying drawings, and to the letters of reference marked thereon, making a part of this specification.

The nature of my invention consists in the construction and arrangement of an egg-carrier, as will be hereinafter more fully set forth.

In order to enable others skilled in the art to which my invention appertains to make and use the same, I will now proceed to describe its construction and operation, referring to the annexed drawing, in which—

Figure 1 is a perspective view of my egg-carrier. Fig. 2 is a longitudinal vertical section, and Fig. 3 a transverse vertical section, of the same.

The egg-carrier box is composed of the bottom A, upon which are erected four corner-posts, B B, and to these posts are fastened parallel slats C C. These slats run around the four sides, and are at such distances apart as to leave suitable spaces between them for ventilation. The box thus constructed contains a series of frames, D D, made in rectangular form, and of such size as to fit between the front and back of the box, and between the corner-posts at the ends, so as to leave a space, a, at each end of the box, between it and the ends of the frames. On top of each frame D is secured a sheet, b, of pasteboard or other suitable material, by means of headed pins x x. The heads of these pins project above the sheet b, and form posts, upon which the frame above rests, thus forming air-spaces between the frames. By this construction of the box and frames a free circulation of air is obtained around the eggs throughout the whole box, and the box is at the same time very cheaply constructed. The tops b b of the frames have circular openings

or holes d d in them to hold the eggs. The holes in one frame do not correspond with those in the frame immediately above and below, so that when an egg is placed on end in one, its lower end rests on the top of the frame beneath it. The frames D D should be made of a height equal to about half the depth of an egg. The box A B C is provided with a hinged lid, G, on the under side of which is secured a frame, D', corresponding in size and position with the egg-frames D D. When the lid is closed down, the frame D' presses down upon the knobs or headed pins x x of the upper egg-frame D, and clamps or holds all of said egg-frames firmly in their places in the box.

I am aware that an egg-carrier box composed of a series of separated strips, and having a lid with a rectangular board on its inside, is not new.

By my construction of carrier-box and arrangement of frames therein, the air will pass between the slats of the box and between each frame, and when the lid is closed the rectangular frame on the inside thereof will bear on edges of the top egg-frame, and clamp the egg-frames within the box, so that they cannot jostle. The eggs of the top egg-frame will not be broken, as they pass between the bars of the frame on the lid.

Having thus fully described my invention, what I claim as new, and desire to secure by Letters Patent, is—

In combination with the egg-carrier box A B C, with lid G and interior frame D', the removable and separate frames D, with perforated sheets b and pins x x, placed one upon the other between the posts B, and leaving the spaces a at the ends, all substantially as and for the purpose herein set forth.

In testimony that I claim the foregoing I have hereunto set my hand this 11th day of August, 1873.

FRANCIS M. HUNT.
